CABLE CONNECTOR

James M. Caffer, Albuquerque, N. Mex., assignor by
mesne assignments, to the United States of America as
represented by the United States Atomic Energy Com-
mission

Filed June 26, 1961, Ser. No. 119,751
6 Claims. (Cl. 339—45)

The present invention relates generally to cable connecting means and more particularly to a coaxial cable connector in which the mating parts are forcibly separated from each other when the connector is in an unlocked condition.

In the cable connector field the electrical connection between two or more conductors is normally attained by placing the connector components together and then in some manner provide a holding or locking relation therebetween for establishing and maintaining an electrical path through the conductors. However, when it is desired to break the electrical path by disconnecting the connector components a serious drawback is sometimes encountered in that when the locking means is in an unlocked condition, it is still possible to leave the conductors electrically connected due to the failure of the connector mating parts from being completely separated from each other. Therefore, it is an important object of the present invention to provide a connector which forcibly separates the connector mating components when the locking means is in an unlocked position, thus precluding any possibility of leaving the conductors electrically connected.

Another object is to provide a connector incorporating a rapid and positive connecting and disconnecting bayonet-type coupling.

A further object is to provide a new and novel clamping means for securely joining a round coaxial conductor to a connector component.

A still further object is to provide a new and novel clamping means for securely joining a flat coaxial conductor to a connector component.

A still further object is to provide a spline locking arrangement for rendering the connector resistant to shock and vibration.

Other and further objects of the invention will be obvious upon an understanding of the illustrative embodiment about to be described, or will be indicated in the appended claims, and various advantages not referred to herein will occur to one skilled in the art upon employment of the invention in practice.

Preferred embodiments of the invention have been chosen for purposes of illustration and description. The preferred embodiments illustrated are not intended to be exhaustive nor to limit the invention to the precise forms disclosed. They are chosen and described in order to best explain the principles of the invention and their application in practical use to thereby enable others skilled in the art to best utilize the invention in various embodiments and modifications as are best adapted to the particular use contemplated.

In the accompanying drawings:

FIG. 1 is a longitudinal sectional view of one form of the assembled connector;

FIG. 2 is a longitudinal sectional view of the connector receptacle portion;

FIG. 3 is a longitudinal sectional view of the connector plug portion containing the round coaxial conductor;

FIG. 4 is a transverse sectional view along lines 4—4 in FIG. 1 illustrating the spline coupling section;

FIG. 5 is a plan view illustrating the bayonet coupling;

FIG. 6 is a transverse sectional view along lines 6—6 of FIG. 1; and

2

FIG. 7 is a longitudinal sectional view showing a modified form of the plug portion which is adapted to contain a flat coaxial cable.

With reference to the embodiment illustrated in FIGS. 5 1—6, the connector of the present invention, generally indicated at 10, comprises a receptacle portion 11, which may be normally fastened to a panel or the like, and a plug portion 12 which may be attached to a round coaxial cable 13 and adapted to engage receptacle portion 11 for establishing an electrical path through the connector 10 to a point of use within said panel.

With further reference to FIGS. 1 and 2 the receptacle portion 11 comprises an insulating bushing member 14 made of any suitable insulating material and having on one end thereof a centrally located recess 15 surrounded by an annular recess 16. A conductor 17, which may correspond to the inner conductor of a coaxial cable, extends through the bushing 14 and is secured thereto in any suitable manner. The conductor 17 terminates at one end adjacent to the base of recess 15 in the form of a "socket" or receptacle 18 and at the other end with an electrical contact 19. An annular terminal member 20 may be securely fastened to contact 19 by crimping a thin portion 21 of the terminal member 20 into a small recess 22 about the periphery of conductor 17. A raised exterior shoulder 23 may be placed intermediate the ends of the bushing 14 for accommodating an encircling metal housing 24.

The metal housing 24 encircles a major length of the bushing 14 and may correspond generally to the outer conductor of a coaxial cable. The housing 24 may be secured to the bushing 14 by providing the housing 24 with a recessed portion 25 having an end wall abutting against one side of the bushing shoulder 23. A relatively thin housing portion 26, which may be provided with screw threads 27 on the outer surface thereof for attaching the receptacle portion 11 to a panel or the like, extends endwise a distance slightly greater than the width of the bushing shoulder 23 and may be peened against the side 28 of shoulder 23 to effect a secure attachment of the housing 24 to the bushing 14. It may be desirable to provide a small slant to bushing side 28 to afford a better seating surface for the peened housing portion 26. While the connection between the housing and bushing is preferably established by a peening operation, it will be obvious to those skilled in the art when practicing the invention that other means of attaching the housing to the bushing will be readily available, such as, for example, a snap ring or the like placed between the side 28 of the shoulder and a groove in the housing portion 26. A flange 30 may be placed on the housing 24 adjacent the housing portion 26 for preventing said portion from passing through the opening in the panel and for the purpose of establishing a tight connection between the threaded housing portion 27 and a nut means (not shown), on the opposite side of the panel. Adjacent flange 30, as best shown in FIG. 4, is a smaller second flange 33 having on its surface a plurality of grooves 34 separated by a pair of lands 35, which function to lock the plug portion

50 12 to the receptacle portion 11 as will be described in detail below. While the groove and land relation above described attains a highly desirable locking arrangement, it will be obvious that many other groove designs with or without separating lands may be used. A small lip 55 36 may also be provided on each of the lands 35 to accomplish a hold-off operation which will be described below. Between the second flange 33 and the other end of the housing 24 is a longitudinally extending recessed housing surface 37 which may contain on the outer surface 60 thereof at least two pins 38 circumferentially spaced 180° apart from each other for establishing a bayonet-type connection with the plug portion 12. While two pins 38

are placed on this surface it will be obvious that any number and arrangement of pins may be used to attain the desired bayonet connection.

With further reference to FIGS. 1 and 3, the plug portion 12 adapted for use with the round coaxial cable comprises a hollow insulating bushing 40 made of any suitable insulating material, which has at one end thereof a slanted end wall 41 and at the other end a centrally recessed longitudinally extending annular portion 42 which is adapted to slide into the annular recess 16 of bushing 14 when the plug portion 12 is joined to the receptacle portion 11. The annular portion 42 cooperates with recess 16 to provide a highly advantageous feature in that when the connector 10 is coupling a high voltage circuit the effective length of the creepage path between the respective conductors is greatly increased by the path formed by portion 42 and the recess 16. The inner conductor 44 of the round coaxial cable 13 is separated from the outer conductor 46 and the cable insulating jacket 47 by a dielectric spacer 45. The inner conductor 44 is preferably slightly longer than the dielectric spacer 45 and may be fastened by soldering or the like to a pin or plug member 48 which is adapted to mate with the "socket" 18 of the receptacle portion 11.

An annular insulating bushing 49 having an outwardly tapered end wall 50 which may be substantially parallel to the slanted end wall 41 of bushing 40 and which may be provided with a threaded inner surface 51 or any other suitable binding means is adapted to be "screwed" or otherwise positioned over the cable jacket 47 so as to cause the threads to "bite" into the jacket 47 and hold the bushing 49 in a desired location on the coaxial cable 13. The inner conductor 44, the dielectric spacer 45 and the plug member 48 are then passed substantially through the hollow bushing 40 to a point where a shoulder 52 engages an inwardly extending lip 53 on bushing 40, thus correctly positioning the plug member 48 with respect to the "socket" 18. The slanted end wall 41 of bushing 40 is adapted to slide between the outer conductor 46, which is preferably of the braided type so as to readily conform to the shape of the slanted end wall 41, to where the outer conductor 46 is tightly held and secured between the tapered wall 50 and the slanted end wall 41. It may be necessary to adjustably move the threaded bushing 49 in either longitudinal direction so as to attain the desired binding effect upon outer conductor 46 between the walls 41 and 51. The cable jacket 47 on the coaxial cable 13 may be terminated near the base of the slanted end wall 41 before the bushing 40 is placed over the inner conductor 44 or just prior to the adjustment of the threaded bushing 49.

To provide the means for forcibly separating the plug portion 12 from the receptacle portion 11 a relatively stiff helically wound compression spring 54 which may be of any suitable type, such as, for example, a spring machined from a soft metal tube by first cutting a narrow helical groove through the tube wall and extending such groove to points adjacent the ends of the spring so as to leave the spring "boxed" in at each end, and then spreading the groove to the desired spring length and finally hardening the spring metal in this desired shape, is positioned around a substantial length of the bushing 40 and abuts a raised shoulder 55 adjacent the bushing end wall 41. The spring 54 has a relatively thin section 56 adjacent the shoulder 55 so as to be substantially level with the latter. This spring, which may provide the main electrical path between the outer conductor 46 and the housing 24 of the receptacle portion 11, is axially compressed as the plug portion 12 and the receptacle portion 11 are joined so as to forcibly eject the plug portion 12 from the receptacle portion 11 when such portions are in an unlocked condition as will be described in detail below. After the spring 54 is positioned on the bushing 40 or at any other suitable time the outer conductor 46 may be terminated

leaving sufficient length for completely covering the thin spring section 56.

A metal sleeve 57 having an inwardly projecting end wall 58 and an inwardly disposed indenture 60 is adapted to slide over the threaded bushing 49 with the indenture 60 mating with a longitudinally extending slot 61 in the surface of the threaded bushing 49, thus preventing the bushing 49 from rotating with respect to the sleeve 57. The sleeve 57 includes a projection 64 which is of sufficient diameter so as to fit over the outer conductor 46 and thin spring section 56 and may be secured in such position by attaching the thin spring section 56 to the sleeve projection 64 by soldering or the like which also securely fastens and electrically couples the outer conductor 46 to the spring section 56. It may be desirable to provide the sleeve projection 64 with small apertures 66 so as to provide a better soldering joint.

A metal housing 68 which is adapted to encircle the entire plug portion 12 and may correspond generally to a supplemental electrical path for the outer conductor of a coaxial cable is provided with an inwardly disposed flange 69 near one end thereof and may be moved into position over the sleeve 57 and spring 54 to where the one side of housing flange 69 abuts the sleeve end wall 58. The inwardly projecting flange 69 contains a plurality of evenly spaced apertures 70 therethrough which are adapted to house a pair of members 71 axially extending from the end wall 58 for preventing rotary movement of the housing 68 with respect to the sleeve 57. Once the housing 68 is moved into place over the spring 54 and sleeve 57 it is held in position by spring lock 72 having a generally frusto-conical shape which may be secured in a slot 73 of the housing 68 by a pressed fit or the like and is biased inwardly so as to engage a shoulder 74 on the spring 54.

A sealing assembly 75 for providing a suitable environmental seal between the cable 13 and the plug portion 12 may be formed from a pressed fit spacer 76 of brass or the like and a pair of annular oversized pre-formed packings 77 and 78 which may be in the form of quadrings or the like and are placed inside the housing 68 adjacent the outer side of the housing flange 69 with the spacer 76 positioned thereagainst. The packings 77 and 78 are held within the interior of housing by an end wall 79 which may be secured to the housing by a pressed fit, soldering, peening a portion of housing 68 over the end wall 79 or in any other suitable manner. By using oversize packings 77 and 78 an adequate seal may be attained due to the packings bearing into the surface of the cable jacket 47.

The end of the housing 68 surrounding the plug member 48 is provided with an elongated recess 80 between two annular shoulders 81 and 82. A compression spring 83 of greater diameter than the forwardly disposed shoulder 81 is placed within the recess 80 to perform a connecting function to be described. The shoulder 81, as best viewed in FIG. 6, may be provided with a plurality of grooves 85 arranged on the periphery thereof and spaced apart from each other by lands 86. A movable sleeve 87 is placed over the housing 68 and encircles the shoulders 81 and 82. The forward portion of the sleeve 87 or the portion nearest the shoulder 81 is smaller in diameter than the spring 83, thus providing a surface or lip 88 which abuts the spring 83 and prevents the sleeve 87 from moving freely rearwardly over the shoulders. The rear portion of the sleeve 87 is slightly greater in diameter than shoulder 82 and may be provided with an annular recess 89, so that when the sleeve lip 88 abuts the spring 83 a locking "snap" ring 90 or the like may be placed in the recess 89 so as to bear against the rear of shoulder 82 and thus provide a suitable sleeve retaining arrangement which will allow the sleeve 87 to move rearwardly against the bias of the spring 83. The inner surface of the forward portion of the sleeve 87

contains a plurality of splines 91 (FIG. 6) which are adapted to engage the grooves 85 in shoulder 81 and prevent free rotary movement of the sleeve 87 when the latter is attached to the housing 68 as above described. The splined inner surface of the sleeve 87 extends forwardly of the shoulder 81 and is arranged to engage the grooves 34 (FIG. 4) in flange 33 of the receptacle portion 11 when the mating operation is performed as will be described below.

The forward portion of the housing 68 is annular in form and is radially spaced from the spring 54, thus forming an annular recess for receiving the housing surface 37. The inner diameter of this forward portion is slightly greater than the outer diameter of the recessed housing surface 37 of the receptacle portion 11. An annular slot 92 is provided on the inner surface of the housing 68 adjacent the end of the forward portion and is of sufficient width and depth so as to house the pins 38 of the receptacle portion when the connector is assembled. A pair of axially extending grooves 93, as best shown in FIG. 5, are circumferentially spaced 180° apart from each other and are cut into the inner surface of the housing 68 for providing communication for the pins 38 between the forward end of the housing 68 and the slot 92. It may also be desirable to provide a pair of slightly concave surfaces 94 in the forwardly disposed wall of the slot 92 so as to provide a better seating surface for the pins 38 in event of operating conditions where shock and/or vibrations are present.

A resilient washer or seal 95 may be placed in a second annular slot 96 on the inner surface of housing 68 to provide a seal between the plug portion 12 and the receptacle portion 11 when they are joined.

With reference to FIG. 7, a modified form of the plug portion 12 is illustrated and differs from the round coaxial cable carrying plug portion 12 by its particular adaptation to a flat coaxial cable. Many parts of the modified plug portion are similar in both structure and function to various parts in the plug portion 12 and will thus be identified by the same reference numerals.

The modified plug portion generally indicated at 100 comprises an annular insulating bushing 101 having a through-going rectangularly shaped passage 103 therein and an outwardly disposed shoulder 104 adjacent one end thereof. A flat cable 105, which may be of any desired design, such as, for example, a flat foil inner conductor 107 positioned between a pair of flat foil outer conductors 108 with each being separated from the inner conductor 107 by a layer of insulating material 109 and with all three conductors being encased in a rectangularly shaped outer insulating jacket 110, may have the conductors separated from each other a sufficient length, i.e., peeled apart so as to leave the inner conductor 107 and the layers of insulating material 109 separate from the outer conductors 108 while terminating the outer insulating jacket 110 adjacent the point of conductor separation, so that the inner conductor 107 and the insulating material 109 may extend through the passage 103 of the insulating bushing 101. The inner conductor 107 which may extend beyond bushing 101 a slight distance is adapted to be fastened to a pin or plug shaped member 111 in any suitable manner, such as, soldering or the like.

An annular insulating member 113 which may extend endwise a length substantially greater than the insulating bushing 101, is adapted to completely encircle bushing 101 and be rigidly attached thereto in any suitable manner, such as, for example, by providing threads 114 on the surface of shoulder 104 which mate with threads 115 on the inner surface of member 113. An inwardly disposed shoulder 117 on the insulating member 113 is adapted to abut a shoulder 118 on the plug member 111 and rigidly secure the plug member 111 in its desired position when the member 113 is joined to bushing 101. An annular extension 42 of the member 113 forms a

central recess 119 and is adapt'd to slide into the annular recess 16 of bushing 14 when the plug portion 100 is joined to the receptacle portion 11.

A compression spring 120, which is adapted to perform its functions in the same manner as compression spring 54 (FIG. 3), may be provided with an annular shoulder 121 near the inner end thereof for rigidly securing the spring 120 in the plug portion 100 as will be described below. The spring 120 may also have a recessed inner portion 122 which is adapted to abut a raised shoulder 124 on the member 113 thus preventing the spring 120 from endwise movement in one direction with respect to the insulating member 113.

Each outer conductor 108 is adapted to be attached to the spring 120 by placing each foil conductor 108 on a portion of a relatively thin annular spring section 125 and securing such conductors in place by encircling the conductors with a sleeve 126 having a plurality of perforations 127 therein and then filling such perforations with solder or any other suitable bonding agent to bind the conductors 108 to the spring 120.

An outer shell or housing 129 corresponding generally to the housing 68 is slipped over the spring 120 to where an inwardly disposed shoulder 130 on the shell 129 abuts the spring shoulder 121. The shell 129 may be held in this abutting relationship with the spring 120 by providing a threaded sleeve 131 which is adapted to be inserted inside of the shell 129 and mate with an internally threaded surface 133 of the shell, thus causing the sleeve 131 to bear against the other side of shoulder 121 to hold the spring 120 rigidly within the shell 129.

A soft rubber cable grommet 135 having a beveled forward edge 136 and a rearwardly disposed shoulder 137 is adapted to surround the flat cable and be positioned within the shell 129 to where the grommet 135 abuts the sleeve 131 and the beveled edge 136 abuts a converging surface 138 on the inner surface of the shell 129. The rubber grommet 135 may be held in its abutting relationship by an externally threaded annular ring 139 which may be inserted inside the shell 129 and mate with an internally threaded portion 140 of the shell 129. A washer or the like 141 may be positioned between the ring 139 and the rubber grommet 135 to substantially eliminate the frictional forces that would occur therebetween. It may also be desirable to bond the rubber grommet 135 to the flat cable by a suitable cement to effect a seal and to help hold the flat cable in its desired position.

The components in the forward end of the plug portion 100 designated by numerals 42, 80, 81, 82, 83, 87, 88, 89, 90, 91, 92, 94, 95 and 96 are similar in design and function to the components of plug portion 12 having like designations in FIGS. 1 and 3-6.

Operation

The assembly of the connector components described below is with reference to the receptacle portion 11 and the round coaxial cable carrying plug portion 12; however the joining of the flat cable carrying plug portion 100 to the receptacle portion 11 may be performed in exactly the same manner.

To assemble the mating parts of the connector, i.e., the plug portion 12 to the receptacle portion 11, it is necessary to pass the annular forward portion of the housing 68 over the recessed housing surface 37 of the receptacle portion 11 and align the axially extending grooves 93 with the pins 38. The plug portion 12 is then moved by gripping the housing 68, which may have a knurled surface thus mating the pins 38 with the grooves 93 and the inner conductor plug 48 with the inner conductor "socket" 18. As such movement takes place, the end of the recessed housing surface 37, which may be slightly tapered to ease alignment, abuts the forward end of compression spring 54, compressing the latter. The splines 91 on the sleeve 87 may at this point be 45° out of alignment with the grooves 34 on flange 33, thus the splines 91 on sleeve 87

merely abut the hold-off lip 36 causing the sleeve 87 to be moved rearwardly against the bias of spring 83. When substantially the limit of pin 38 travel in the grooves 93 is attained, the entire plug portion 12 is rotated 45° in either direction, moving the pins 38 circumferentially in the annular slot 92. Simultaneously with the completion of such rotation and with the alignment of splines 91 with the grooves 34, the spring biased sleeve 87 "snaps" forward to mate the splines 91 with the grooves 34. The resilient gasket 95 engages the tapered portion of the recessed housing surface 37 and is sufficiently deformed so as to provide a seal between the mating parts. While the splines 91 are disclosed as normally being 45° out of alignment with the grooves 34, it will be obvious to others skilled in the art to use any desired degree of spline and groove misalignment; in fact, by merely preventing the sleeve 87 from "snapping" forwardly to engage the splines 91 with the grooves 34 when the 45° of rotation is attained, it is possible to place the pins 38 in any desired location within the slot 92.

When the mating parts of the connector are thus assembled, it will be seen that the plug portion 12 is securely locked to the receptacle portion 11, since the pins 38 within the annular slot 92 prevent relative longitudinal movement of either mating part. Furthermore, the pins 38 are retained in place within the slot 92 due to the engagement of splines 91 with grooves 34, thus preventing rotational movement of either mating part which could move the pins 38 into alignment with the grooves 93 causing disengagement. The spring 54, due to its contact with the housing 24 and its connection to the outer conductor 46 acts to hold the pins 38 against the concave surface 94 and also serves as the main current path for the outer conductor of the coaxial cable 13 while the outer portion of the connector serves as the secondary current flow path.

To separate the mating parts for terminating the electrical path through the connector the sleeve 87, which may have a knurled surface for providing an adequate gripping surface, is moved rearwardly against the bias of spring 83 until the splines 91 are moved entirely out of the grooves 34. The plug portion 12 is then rotated in either direction until the pins 38 are aligned with the grooves 93. The compression spring 54, which is in a loaded or compressed condition, instantly imposes a repelling force between the mating parts to rapidly separate the plug portion 12 from the receptacle portion 11, thus precluding any possibility of leaving the conductors of the plug portion 12 electrically connected to the conductors of the receptacle portion 11.

It will be seen that by providing the flange 33 with substantially more grooves 34 than there are splines 91 on sleeve 87 attains a highly desirable feature in that after the pins 38 are sufficiently within the grooves 93 the plug portion 12 may be rotated in either direction to effect engagement of the splines 91 with the grooves 34. The excess number of grooves 34 also cooperate with the concave wall 94 of the slot 92 to provide a novel arrangement especially when the connector is subjected to shock loads. If the connector 10 receives a severe enough shock in a given direction it is highly possible for the sleeve 87 to slide rearwardly and cause disengagement of the splines 91 with the grooves 34; however, due to the concave wall 94 the pins 38 will not move towards the grooves 93 but will tend to seek the innermost point of the concave surface and as the shock force is relieved the sleeve 87 "snaps" back, again mating the splines 91 with the grooves 34. Also by varying the number and arrangement of the pins 38 and grooves 93 on each connector where several connectors are to be used in close relationship to each other suitably sets forth a means of preventing cross-plugging.

As various changes may be made in the form, construction and arrangement of the parts herein without departing from the spirit and scope of the invention and without sacrificing any of its advantages, it is to be understood

that all matter herein is to be interpreted as illustrative and not in a limiting sense.

I claim:

1. A device of the character described comprising in combination a pair of mating portions, one of said portions having an insulating member with a centrally located throughgoing conductor therein and an annular externally disposed shoulder means intermediate the ends thereof, a metal shell surrounding a portion of said insulating member and secured to said shoulder means, annular flange means projecting radially from the surface of said shell and having a groove therein, pin means projecting from the surface of said shell intermediate said flange and one end of said shell, an annular longitudinally extending recess within said insulating member and communicating with one end of said member adjacent said one end of the shell, the other of said mating portions having an insulating means including an annular longitudinally extending portion adapted to engage said recess and a centrally located throughgoing conductor arranged to mate with said first mentioned conductor providing a first current path, a helical compression spring encircling a portion of said insulating means and adapted to abut an outwardly extending shoulder thereon, one end of said compression spring arranged to engage said one end of the shell and resist the mating of said portions, a second conductor in the other of said portions being coaxially disposed with respect to the second mentioned conductor and secured to the other end of said compression spring providing a second current path through said spring and said shell, another shell surrounding said spring and insulating means and having a pair of outwardly disposed and longitudinally spaced shoulders thereon one of which contains a groove in the outer surface thereof, means for securing said other shell to spring, bias means disposed between said shoulders and having a diameter greater than the diameter of said grooved shoulder, sleeve means adapted to surround said shoulders with an inwardly disposed lip abutting one end of said bias means and having an inner surface with a spline projecting therefrom for engaging the groove in the grooved shoulder, said inner surface having a longitudinal length substantially greater than said grooved shoulder so as to enable said spline to engage the groove in said flange, said other shell and said insulating means forming an annular recess for admittance of said first mentioned shell and pin means, said other shell having disposed on the inner surface and adjacent one end thereof a circumferentially extending groove with a longitudinally extending slot communicating said one end thereby permitting said pin means to enter said circumferentially extending groove through said slot and subsequent rotation of said other portion moves said pin means circumferentially within said shell groove away from said slot and aligns the groove in said flange with the spline in said sleeve causing said bias means to urge said spline into said flange groove.

2. The device claimed in claim 1 wherein a plurality of grooves separated by lands are disposed on the surface of said flange and said grooved shoulder, and with said splined sleeve having a lesser number of splines cooperating with said plurality of grooves.

3. The device of claim 1 wherein a locking ring is positioned between one side of the other shoulder on said other shell and an annular groove on the inner surface of said sleeve thereby preventing said sleeve from excessive endwise movement in one direction.

4. The device claimed in claim 1 wherein said coaxially disposed conductor is annular in form and separated from the second mentioned conductor by a cylinder of dielectric material, said annular conductor is secured to said spring by a sleeve means having an inwardly extending endwall with a pair of laterally extending projections thereon and an indenture in a surface thereof and an insulating means having a recess in an outer surface adapted to mate with said indenture and arranged to abut said

sleeve endwall thereby holding said annular conductor against an inclined end surface of said first mentioned insulating means, said other shell has an inwardly disposed and perforated flange adapted to receive said lateral projections, and sealing means is provided between said perforated flange and the other end of said other shell.

5. The device claimed in claim 1 wherein said coaxially disposed cable comprises a pair of flat foil-like conductors normally separated from the second mentioned conductor by a pair of flat insulating members, each of said foil-like conductors is secured to said spring by a perforated sleeve means adapted to hold said foil-like conductors against a surface of the other end of said spring by bonding material within said perforations, said means for securing the other shell to said spring comprises an annular 15 radially extending shoulder on said spring with one side surface thereof adapted to abut a recess in said other shell with a threaded annular sleeve means engaging a threaded inner surface on said other shell adapted to abut the other

side surface of said spring shoulder, resilient means surrounds said flat cable and is positioned within said other shell against one end of said threaded sleeve and abuts a converging inner surface on said other shell, and means wherein means is adapted to hold said resilient means within said other shell.

6. The device claimed in claim 1 wherein said circumferentially extending groove is provided with a concave sidewall forming a seating surface for said pin means.
